UNITED STATES PATENT OFFICE.

E. I. HANON-VALCKE, OF PARIS, FRANCE.

MILLSTONE.

Specification of Letters Patent No. 8,037, dated April 15, 1851.

To all whom it may concern:

Be it known that I, E. I. HANON-VALCKE, of Paris, in the Republic of France, have invented certain new and useful Improvements in Millstones, and that the following is a full, clear, and exact description thereof, reference being had to the accompanying drawings, making part of this specification, in which—

10 Figure 1, is a plan of my improved stone; Fig. 2, a view of the under side, and Fig. 3, vertical section taken at the dotted line A, *a* of Fig. 2.

The same letters indicate like parts in 15 all the figures.

The object of my invention is to secure the introduction of air between the stones in sufficient quantities to prevent the grain from heating in the process of grinding and 20 to keep the pollen in a perfect state of freshness, which is the only means by which the substantial parts of the grain can be preserved from alteration.

Mill stones have been made prior to my 25 invention with metal funnels, (three or more) fixed at equal distances upon the runner in such a manner as to force in air by the effect of the rotary movement, the funnels passing obliquely through the entire thickness of the runner, and entering channels cut in its under surface, by which means, air may be in a measure supplied to 30 keep the grain cool. But this arrangement is far from being perfect for the reason that sufficient air cannot be carried between the stones for want of draft. To remedy this 35 defect, my invention consists in combining with the oblique channels cut through the body of the stone and the furrows in the face thereof, starting from the foot of said 40 oblique channels the use of a vertical draft tube or pipe passing directly up through the runner from near the extremity of the channel in the face of the stone, by which means a continuous draft is supplied, carrying off the heated air from the grain which 45 is being ground and causing cold air to rush in through the oblique channels to keep the grain cool.

50 In the accompanying drawings three or four funnels A, according to the diameter of the mill stones, are placed at equal distances upon the runner B, in such a manner that air will be forced in by the rotation. The necks of these funnels enter aper- 55 traversing it obliquely. These passages ter-

minate in channels or funnels G, cut in the face of the runner. The said apertures are so located that their point of departure is found at 10 inches from the circumference, and their point of termination eight inches, when they are not wider than one inch, and the depth of the furrow at which it terminates, in such a manner that their depth and width continually diminishing describe 60 a curve.

Near the extremity of each channel a cylindrical opening D is formed traversing almost perpendicularly the mill stone in such a manner as to enter the funnel correspond- 65 ing with this opening. In this opening is placed a metal tube of the diameter of 1 $\frac{1}{2}$ inches entering the lower side of the funnel of the next aperture or passage, and even with it, having a screw in the interior, on 70 which can be secured a crooked spout E, the aperture of which is toward the rear, so that the current entering the one funnel will have the effect to exhaust the next aperture, and thus insure a current of air through the 75 apertures or passages.

The action of this apparatus can be easily understood. The air being compressed in the funnels by the rotatory movement and more abundant in proportion to the rapidity 80 of the rotation is driven into the channels which traverse the furrows of the runner, and pass continually between the mill stones. This air being sent toward the circumference by the effect of the centrifugal 85 movement, traverses necessarily over the whole of the working part of the mill stones, sweeps over their sides, rushes into the furrows and penetrates between the rough surfaces of the mill stones, mixes with 90 the meal and rolls with it into the conduits. This air, always fresh and continually re-newed, receives a new activity by the circu- 95 lation which the pipes placed at the extremiti- 100 es of the channels give to it. This circulation can be increased or diminished at will by means of the spouts E which can be turned to reduce the exhausting action. By means of this circulation of the air, a part of the mill dust might be put into 105 movement and carried through the open- 110 ings intended to increase the circulation. The spouts of the pipes are placed in such a manner as must drive back the light par-ticles of the flour into the bottom of the funnels and these instantly send them be-tween the mill stones from whence they soon

pass with the rest of the meal into the receptacles which direct the meal toward the bolting machine.

What I claim as my invention and desire 5 to secure by Letters Patent is—

Constructing the running stones of mills with oblique apertures or passages through the body of the stone and provided with hoods or funnels to collect the air during 10 the rotation and connected on the grinding face of the stone with furrows, substantially

as described, when this arrangement is combined with the use of vertical pipes leading from the extremity of one of the apertures or passages to a funnel leading to the next 15 succeeding oblique passage in the body of the stone substantially in the manner and for the purpose specified.

E. I. HANON-VALCKE.
